(57) **CLAIM**

The ornamental design for a mobile communication device, as shown.

DESCRIPTION

FIG. 1 is a front perspective view thereof;
 FIG. 2 is a front side view thereof;
 FIG. 3 is a rear side view thereof;
 FIG. 4 is a left side view thereof;
 FIG. 5 is a right side view thereof;
 FIG. 6 is a top plan view thereof;
 FIG. 7 is a bottom plan view thereof; and,
 FIG. 8 is a rear perspective view thereof.
